UNITED STATES PATENT OFFICE.

ARTHUR T. CRANE, OF WATERBURY, CONNECTICUT, ASSIGNOR TO THE CHASE COMPANIES INC., OF WATERBURY, CONNECTICUT, A CORPORATION.

VISIBLE SPARK PLUG.

1,425,749.

Specification of Letters Patent. Patented Aug. 15, 1922.

Application filed March 5, 1921. Serial No. 449,780.

To all whom it may concern:

Be it known that I, ARTHUR T. CRANE, a citizen of the United States, residing at Waterbury, in the county of New Haven and State of Connecticut, have invented a new and useful Improvement in Visible Spark Plugs; and I do hereby declare the following, when taken in connection with the accompanying drawings and the characters 10 of reference marked thereon, to be a full, clear, and exact description of the same, and which said drawings constitute part of this application, and represent, in—

Fig. 1 a view in side elevation of one 15 form which a visible spark-plug embodying my invention may assume.

Fig. 2 an enlarged plan view thereof.

Fig. 3 an enlarged broken view of the 20 upper end thereof partly in vertical central section and partly in elevation.

Fig. 4 an enlarged view in transverse section on the line 4—4 of Fig. 1.

Fig. 5 a detached view of the terminal-cap partly in side elevation and partly in 25 vertical section before the spinning inward of its beads.

Fig. 6 a detached perspective view of the 30 sparking-disk.

Fig. 7 a detached edge view of the lens.

35 My invention relates to an improvement in that class of visible spark-plugs in which the terminal-screw is located directly above and in line with the electrode, so as to permit the socket-wrench employed for installing and removing the plug to be axially passed down over the plug and lifted off the same, the object of my present invention being to produce a single, compact and durable plug, composed of few parts, convenient in use and reliable in performance.

40 With these ends in view, my invention consists in a visible spark-plug having certain details of constructions and combinations of parts as will be hereinafter described and pointed out in the claims.

45 In carrying out my invention as herein shown, I employ a sparking-disk 10, having its center struck downwardly to form a conical sparking-boss 11, and formed with 50 three segmental observation-openings 12, grouped in a circle around the said boss, equally spaced apart and registering with three corresponding observation-openings 13 formed in the concavo-convex upper wall 14 55 of the lens-chamber 15 of a sheet-metal

mounting-cap 16, the said chamber receiving a plano-convex lens 17, which fills the said chamber, and the flat lower face of which rests upon the upper face of the said disk, the edge of which rests upon an inwardly-projecting annular bead 18 spun in the metal of the cap 16 after the introduction of the said lens and disk into the said lens-chamber.

Under the construction described, the user 60 of the plug is enabled to look downward through the observation-openings 13,

through the lens 17, and through the observation-openings 12 in the disk and observe the electrode 19 in the sparking-chamber 20, which is located directly below the lens-chamber and furnished with a plurality of ventilating openings 21,

through which the ozone escapes to prevent the discoloration of the lens and which also 70 permits the operation of the plug to be observed, the sparking-chamber 20 being illu-

minated by the passage of the spark from the electrode 19 to the sparking-boss 11 of the sparking-disk 10. An inwardly-projecting annular spacing-bead 22, spun into the 75 metal of the cap 16, rests upon the upper edge of the core 23 and mounts the cap 16

in correct position thereupon, so as to produce the sparking-chamber 20, which occupies the space between the sparking-disk 10 80 and the upper face of the core, to which the cap is secured by spinning its lower edge into an annular groove 24 therein for the production of the retaining-flange 25. As 85

shown, the mounting-cap 16 is spun to form at its upper end, a concentric, hollow boss 26 rising from the concavo-convex wall 14 of the lens-chamber and in turn formed with a concentric, hollow terminal-screw 90 95 mounting the terminal-nut 28, but if preferred the screw may be made independent of and rigidly mounted in the mounting-cap in the well-known manner.

I would have it understood that I do not 100 limit myself to the exact structure herein shown and described, my present invention being directed to the use of a sparking-disk formed with observation-openings register-

ing with corresponding observation openings 105 formed in a portion of the mounting-cap.

I claim:

1. A visible spark-plug having its cap provided with a lens-chamber and with observation-openings leading thereinto, a lens 110

in the said chamber, and a sparking-disk formed with observation-openings aligned with those in the cap, the said observation-openings of the lens-chamber and sparking-disk being located at one side of the longitudinal axis of the plug, in which direction the sparking takes place.

2. A visible spark-plug having a sparking-chamber, an electrode projecting thereinto, a sparking-disk having a sparking-point located in line with the axis of the electrode, and provided with observation-openings located at one side of its center, and a lens-chamber having corresponding observation-openings located at one side of its center and registering with the said observation-openings in the sparking-disk.

3. A visible spark-plug having a sparking-chamber, an electrode projecting thereinto and a sparking-disk located above the sparking-chamber and formed with a concentric downwardly projecting sparking-boss for co-action with the electrode, and with observation-openings through which the interior of the sparking-chamber may be observed.

4. In a visible spark-plug, the combination with a mounting-cap comprising a sparking-chamber, and a lens-chamber lo-

cated above the same and having a concavo-convex upper wall formed with observation-openings located at one side of its center; of an electrode projecting into the said sparking-chamber, a lens located in the said lens-chamber, and a sparking-disk interposed between the said chambers and formed with a centrally-arranged sparking-boss located in line with the said electrode, and with observation-openings located at one side of its center in position to register with the observation-openings in the concavo-convex wall of the lens-chamber.

5. A visible spark-plug having a lens-chamber, a sparking-chamber, an electrode projecting into the said sparking-chamber, a lens located in the lens-chamber, and a sparking-disk interposed between the said chambers and provided with a sparking-point located in line with the axis of the electrode.

In testimony whereof, I have signed this specification in the presence of two subscribing witnesses.

ARTHUR T. CRANE.
